UNITED STATES PATENT OFFICE

DREXEL J. SCOTT, OF YOUNGSTOWN, OHIO

PROPELLER-REVERSING DEVICE

Application filed September 30, 1927. Serial No. 223,097.

The present invention relates to an improved device for reversing propellers used on aeroplane, aircraft of other kinds, boats, and the like.

5 The principal purpose of the invention is to provide a means for reversing the action of the propeller of the aeroplane to give a braking effect.

10 The device will enable the operator or pilot to change the pulling power of the propeller to a pushing power, only limited by the speed of the engine.

15 When the blades are in the "retard" position, the propeller will have a tendency to push the air away from it and consequently slow up the forward motion of the machine. By speeding up or slowing down the engine, this effect can be easily governed. The direction of the rotation of the blades can be 20 changed to forward or retard positions, at the will of the pilot through means of appropriate operating devices, such as lever or foot pedal.

25 The primary object is to enable a plane to come to earth at normal speed and immediately upon contact with the earth, the operator may turn the blades of the propeller over one-quarter turn to retard position. He can then speed up the motor and come to a quick 30 stop, without waiting for the plane to come to a standstill governed by the momentum.

With this device, it is therefore possible to use the same power to stop as it is to start the plane in motion.

35 Another use is to provide the operator with an effective brake while flying in midair to avoid collision. It is possible through the use of this device to come to a substantially 40 complete stop in the air, and then drop out of the way of an oncoming plane for instance.

It could offer many advantages for quick 45 maneuvering of combat planes in time of war. The foregoing and other objects and advantages of the invention will become more readily apparent from the following description and drawings.

In the drawings:—

50 Figure 1 is a top plan view of a propeller

reversing device constructed in accordance with the present invention.

Fig. 2 is a fragmentary elevational and sectional view showing the internal mechanism more plainly and the relative arrangement and association of parts. 55

Fig. 3 is a longitudinal section through the central portion of the device.

Fig. 4 is an elevational view of the stationary hub section. 60

Fig. 5 is an end view of one of the propeller actuators.

Fig. 6 is a side view of said actuator.

Referring now to the drawings by numerals, it will be seen that the reference character 65 7 designates a crank shaft whose outer end is tapered. Mounted on this crank shaft is the stationary section 8 of a novel hub structure. This section is fastened to the crank shaft through the medium of a key 9 and a 70 retaining nut 10. It includes a reduced portion 11 constituting a bearing sleeve, a substantially cylindrical intermediate portion 12, and a disk-like abutment 13.

Carried by the portion 12 are longitudinal 75 circumferentially spaced ribs 14, also functioning as keys. As shown in Fig. 4, this hub section is provided on opposite sides, with a somewhat ovate hole 15, and a cooperating arcuate cam slot 16.

The relatively movable section 17 of the hub structure is somewhat slidably mounted 80 on the rigid section 8 for rotating with the rigid section. It includes a central cup-like portion 18 having internal key-ways receiving the aforesaid keys 14, and having a grooved neck portion 19 slidable on the aforesaid bearing 11, as shown in Fig. 3.

In addition, it is provided with a pair of 85 right angularly extending duplicate sockets 20 as shown in Figs. 1 and 2, each socket being provided with an appropriate lining 21. Mounted in each socket, for oscillation is a journal or actuator 22, of hollow construction. This actuator is provided on its inner 90 end with a fulcrum pin 23 extending into the aforesaid hole 15, and a cam pin 24 extending into the cam slot 16. The outer end thereof, which is screw threaded, and counter-bored, as at 25, extends outwardly beyond 100

the socket to permit the stub of the propeller blades 26 to be fastened thereto.

This screw threaded portion 25 is preferably longitudinally split and is clamped on the stub of the propeller blade through the medium of a retaining nut 27 held in place by lock-screws 28. The propeller blade is of customary construction.

Attention is also invited to a removable closing plate 29 for the outer end of the socket, appropriate packing, and a thrust bearing 30 seated in a counter-recess at the outer end of the socket. Incidentally it will be noticed that the journal 22 is shouldered for cooperation with this thrust bearing, the bearing being constructed to take up end thrust, as well as radial thrust.

In practice, an operating lever, or a foot pedal (not shown) is of course provided, and will be in turn provided with means for cooperation with the grooved head 19 of the slid able hub section 17. It might be stated, that this hub section has a very slight movement, and can be slid in an outward direction until it abuts the disk 13.

With the arrangement described, it is of course obvious that when the section 17 is slid outwardly on the rigid section 8, the cam action produced by the cam slots 16, and operating pins 24, serve to rotate the journals or actuators 22. In so doing, the propeller blade is rotated through an approximate quarter turn, thus reversing its action in order to accomplish the results specified at the outset of the description.

The construction and operation of the invention, will be quite clear to persons skilled in the art to which it relates. Therefore, a more lengthy description is believed unnecessary.

Minor changes in shape, size, and rearrangement of parts coming within the field of invention claimed, may be resorted to if desired.

Having thus described my invention, what I claim as new is:—

In a propeller changing device of the class described, a rotary crank shaft, a hub structure including an inner stationary section rigidly fastened to said crank shaft and including an abutment disk at its outer end together with circumferential longitudinally extending keys, an outer slid able hub section mounted on the first-named section and including keyways receiving said keys, together with outstanding sockets, propellers disposed in axial alinement with said sockets, and including journals mounted for oscillation in the sockets, said journals having fulcrum connections at their ends with the stationary section of the hub, said stationary sections being provided with arcuate cam slots, and cam pins carried by said journals and movable in said slots, and retaining means

carried by the outer ends of said sockets and cooperable with said journals for maintaining the journals in assembled relation.

In testimony whereof I affix my signature.

DREXEL J. SCOTT.
